(57) **CLAIM**

The ornamental design for a valve lockout, as shown and described.

DESCRIPTION

FIG. 1 is an isometric view of a top, front, and left side of an ornamental design for a valve lockout;

FIG. 2 is an isometric view of a bottom, rear, and right side of the valve lockout of FIG. 1;

FIG. 3 is a front elevational view of the valve lockout of FIG. 1;

FIG. 4 is a rear elevational view of the valve lockout of FIG. 1;

FIG. 5 is a right side elevational view of the valve lockout of FIG. 1;

FIG. 6 is a left side elevational view of the valve lockout of FIG. 1;

FIG. 7 is a top plan view of the valve lockout of FIG. 1; and, FIG. 8 is a bottom plan view of the valve lockout of FIG. 1. The dash-dash broken lines are included for the purpose of illustrating portions of the valve lockout that form no part of the claimed design.

1 Claim, 8 Drawing Sheets
